METHOD AND SYSTEM FOR REFRIGERATION OF RAILROAD CARS

Robert D. Pike, Greenwich, Conn.

Application February 18, 1948, Serial No. 9,053

3 Claims. (Cl. 62—91.5)

1

The present invention relates to a cooling system for and a method of cooling a refrigerator car, and more particularly to a cooling system and method in which refrigeration is provided by sublimation of solid carbon dioxide, or Dry Ice, in conjunction with water ice.

An object of the present invention is to provide general purpose refrigeration for railroad cars for the shipment principally of fresh fruits and vegetables wherein a non-freezing refrigerating temperature is desired, and in which the main source of refrigeration is derived from the sublimation of Dry Ice.

Another object of the invention is to provide a system for cooling a refrigerator car by which air circulated in the car is cooled by contact with water ice causing the latter to melt thereby limiting the minimum air temperature to 32° F., and reducing the normal rate of melting of the water ice by the sublimation of solid carbon dioxide, the system being adapted to minimize the rate of sublimation of the solid carbon dioxide, so that some water ice will always melt and so that a single icing of the refrigerator car will be sufficient for seven to ten days while maintaining a non-freezing refrigerating temperature of the foodstuffs in the car.

A still further object of the invention is to provide a refrigerating system utilizing a refrigerating medium comprised of a combination of solid carbon dioxide and water ice and in which system air may circulate by gravity or by force into contact with the refrigerating medium, the path of the gravity circulation being substantially solely confined to contact with the water ice while the path of forced circulation is to a substantially greater degree in heat exchange relation with the solid carbon dioxide as well as in heat exchange relation with the water ice.

A further object is to provide split, or two compartment bunks, on each end of the car, the compartments of each bunker being separated by an insulated wall running across the car and utilizing the two compartments at the ends of the car which are most remote from the goods in the car, for the storage of Dry Ice.

Other objects and advantages of my invention will become apparent from the following description of a preferred form of the invention, reference being made to the accompanying drawings wherein:

Fig. 1 is a fragmentary, vertical longitudinal section through the center line of a railway car, only one end of which car is shown;

Fig. 2 is a view in section taken on the line 2—2 of Fig. 1; and

2

Fig. 3 is a view in section taken on line 3—3 of Fig. 1.

In the drawings 10, 11, 12 and 13 represent the end walls, roof, floor and side walls, respectively, of an insulated railroad car which may be of standard construction in this respect. The structures at opposite ends of the car are identical and therefore only one such structure is shown and described. Each end of the car is provided with an ice bunker which is formed by a bulkhead 14 spaced from the end wall of the car. The upper portion of the bulkhead is open for the passage of air and louvers 15 are provided for distributing the air into the upper portion of the goods storage space, indicated at C. The lower edge of the bulkhead is spaced from the car floor to form an air passage therethrough as indicated at 16. A perforated flooring 17, which may be in the form of gratings, is provided above floor 12 and extends throughout the car intermediate the bulkheads 14 and this flooring supports the load in the car and provides an air passage beneath the load leading to the openings 16. The perforations in the flooring permit passage of air through the bottom of the storage space throughout the latter. A fan 18 is disposed at each end of the car beneath flooring 17 for forcing air towards the ends of the car through opening 16. Preferably, the fan is driven by the car axles through belts, not shown, and operate only when the car moves.

The bunkers are each divided into two compartments B¹ and B² by a vertically extending wall 20 which extends transversely of the car. Preferably, the wall 20 is formed of a steel plate 21 having two inches of high grade thermal insulating material 22 attached to the surface. The inside side surfaces of compartment B¹ are covered with plywood, as shown at 23, for protecting the insulating material. The compartment B¹ is located remote from the food storage space and it is adapted to receive pulverized solid carbon dioxide, hereinafter referred to as Dry Ice, and compartment B², which is adjacent to the storage space C is adapted to receive water ice. The two ice compartments can be filled through a hatch 25 in the top of the car, the top of the wall 20 terminating short of the hatch to provide access to both compartments. A screen 26 is hinged to the top of the wall 20 and this screen may be swung from one side to the other of the hatch for directing ice into either compartment, as desired.

The bottom wall 27 of the Dry Ice compartment B¹ is formed of heat conducting material, such as a 10 gauge steel plate which may be pro-

vided with heat transfer fins 28. The plate 27 is preferably supported about 20 inches above the floor of the car which is well above flooring 17.

A water ice grate 30 of usual well known design, forms the bottom of compartment B² and it is supported at the same level as bottom plate 27. The load of water ice in the compartment B² is kept at least about two inches away from the bulkhead by the usual well known ice screening 31, which extends vertically from grating 30 to the top of the car and transversely of the car and which maintains a minimum vertical air passage between the water ice and the bulkhead 14.

A horizontally extending plate 33 extends from the lower edge of the bulkhead 14 toward the near end of the car and it projects slightly less than half the distance from bulkhead 14 to wall 20 of compartment B². The plate 33 extends the width of the car and it serves to direct the impelled air from fan 18 toward the end of the car beneath the bottom wall 27 of the Dry Ice compartment B¹ and along the bottom of compartment B² and upwardly between the water ice and bulkhead 14. When the air flow is in the reverse direction, the plate 33 will permit substantially all of the air flow to bypass the bottom of compartment B¹ and flow from the water ice directly into the goods storage space. This occurs because the flow of air is by convection and the velocity is not sufficient to impel the air flow beneath the Dry Ice compartment.

In practice I usually fill the Dry Ice compartment B¹ with pulverized Dry Ice, usually about 2,750 pounds per compartment, or 5,500 pounds per car, but I may use less when the average outside temperature falls below the maximum summer average, as in the spring and fall. This Dry Ice is pulverized in a manner similar to that sometimes employed with water ice and blown into the compartment. I may then close the compartment with a cover, not shown, which may have a pipe connection to bleed the CO₂ out of the car, or merely a vent to allow it to escape into the car, as may be preferred. I then move the screen into place, as shown, for filling line B² with water ice and then fill this bin to the level of the bottom of the hatch coping with about 3,700 pounds coarse water ice. It will be observed that both the water ice and Dry Ice are loaded through the top hatches of the car. However, in some cases, I may find it more convenient to first load the water ice compartment with water ice at the time the car is loaded, thence moving the car to a Dry Ice depot, filling the Dry Ice compartment and refilling the water ice compartment to its full capacity as may be indicated.

When the car is in transit the fan 18 is actuated by the axle and it withdraws air from the bottom of the goods storage space and from side wall flues, not shown, if installed and blows it as indicated by the full line arrows underneath baffle 33. The inertia of this air stream causes it to strike the end wall of the car, whence it is diverted upwardly into contact with the heat transfer plate 27 under the Dry Ice compartment, beneath the water ice compartment, upwardly between the water ice surface and bulkhead 14 and into the upper part of the goods storage space from where it is drawn downwardly through the goods, cooling the latter.

The plate 27 rapidly becomes covered with a layer of water ice, or frost, which reduces heat transfer into the Dry Ice, thus tending to reduce its rate of sublimation. This end is further aided

by the relatively small area of the plate, which is only about 10 sq. ft. This reduction of the rate of sublimation of the Dry Ice tends to increase the meltage of water ice, thus insuring that the contact surfaces between the circulating air and the water ice shall always be at the true freezing point, or 32° F.

After the car has been in service a few hours, the water ice in compartment B¹ becomes tightly frozen against plate 27 by the passage of heat into the Dry Ice through the insulated partition wall 20, and furthermore, meltage within the water ice becomes frozen to such an extent aided by the deposition of frost that most of the flow of air is constrained to pass between vertical surfaces of the water ice and the inner surface of the bulkhead 14. At first this flow occurs necessarily in the 2-3' space back of screen 31, but as meltage proceeds the face of the water ice remains substantially vertical and recedes from the screen, as is illustrated in Fig. 1. Thus most of the meltage of water ice is caused by the passage of the air over this vertical surface of the ice and as all of the air does so pass, it is continually in contact with surfaces which are necessarily at a temperature of about 32° F. The result of this is that the air maintains a minimum temperature in the goods storage space of about 33-35° F. when the fan is operating.

When the fan is shut off for any reason, the direction of the air reverses itself and becomes downstream, flowing by the vertical water ice surface, thence around the baffle 33, which is made short so that a substantial portion of the air will by-pass the plate 27, which would otherwise tend to cool it below 32° F. This flow of air is indicated by the dotted arrows. The transfer of heat from the very small portion of naturally flowing air which may come into contact with plate 27 is greatly impeded by the layer of frost on this plate. Thus, air entering the goods storage space through the floor by convection will be in the neighborhood of 32° F., but no lower.

Because the major flow of air through the car occurs only with the fan on, the conditions then prevailing are the ones which mainly determine the satisfactory operation of my system. However, I have shown that even when the fan is off, the air which flows by natural circulation and in relatively small volume is diverted away from surfaces cooled by Dry Ice.

An example of the operation of my system is outlined hereinafter from conditions which prevailed during a test of a refrigerator car embodying my invention.

Speed of car	30 miles per hour
Duration of time when observations were made	62 hrs.
Approximate movement of air by two fans per car	2200 c.f.m.
Maximum temperature of air average at 12 points in the car	35.6° F.
Minimum temperature of air average at 12 points in the car	34.7° F.
Average temperature of air at 12 points	35.3° F.
Water ice meltage, pounds per hour, per car	6.5
Water ice placed in bunkers at start	7400 lbs.
Life of water ice based on 25% consumption	285 hrs.
Life of water ice based on 100% consumption	1140 hrs.
Dry Ice placed in bunkers at start	5500 lbs.

Dry Ice sublimation, pounds per hour, per car	27.8
Life of Dry Ice based upon 100% consumption	198 hrs.
Water ice equivalent of Dry Ice, pounds per hour per car	53.1
Total hourly ice consumption, pounds equivalent water ice, per hour per car	59.6
Type of car insulation	Standard
Maximum outside temperature during test	95° F.
Minimum outside temperature	59° F.
Average outside temperature	74.5° F.

The efficiency and effectiveness of my system is well proven by these data which show that under severe summer temperature the Dry Ice will last about eight days and that one quarter of the water ice only will be melted in about twelve days. The results make it possible to ship a car across the continent without re-icing; also the very small difference between maximum and minimum temperatures in the air in the car prove that enough water ice melts to control the temperature at a desired level between 30°-40° F., neither high enough to cause deterioration of the goods, nor low enough to cause them to freeze.

Although I have described but one form of the invention, it is to be understood that other forms might be adopted, all falling within the scope of the claims which follow.

I claim:

1. A refrigerated car comprising in combination, a compartment providing a food storage space; a bunker at one end of the compartment, said bunker being open to the compartment at top and bottom and having a partition therein dividing the bunker into two contiguous ice storage bins, said bins having the bottom walls thereof spaced from the floor of the car, the bottom wall of the bin remote from the compartment being of heat conducting material and adapted to support Dry Ice; a perforated wall spaced from the bunker wall adjacent to the compartment for forming a water ice retaining wall in the bin adjacent to the compartment and providing an air passageway along the side of the last mentioned bin and said bunker wall leading from the bottom of the bin to the upper opening in the bunker; baffle means forming an air passageway leading successively from the bottom of the compartment through the lower opening of the bunker, into heat exchange with said bottom wall of the remote bin, under the bottom wall of the other of said bins, and to said air passageway; and blower means for forcing air through the passageway in the upward direction.

2. A refrigerated car comprising in combination, a compartment providing a food storage space; a bunker at one end of the compartment, said bunker being open to the compartment at top and bottom and having a vertical partition

therein for dividing the bunker into two ice storage bins, said bins having the bottom walls thereof spaced from the floor of the car, the bottom wall of the bin remote from the compartment being of heat conducting material and adapted to support Dry Ice; a vertical perforated wall spaced from the wall of the bunker wall adjacent to the compartment for forming a water ice retaining wall in the bin adjacent to the compartment, and for providing a minimum vertical air passageway along the side of the last mentioned bin and said member leading from the bottom of the bin to the upper opening in the bunker; a baffle plate extending into the bunker from the bottom opening in the bunker and parallel to the bottom of the last mentioned bin and intermediate the floor of the car and said bottom for forming an air passageway leading from the bottom of the compartment to beneath the ice bins and reversing to traverse said bottom wall of the remote bin and the bottom wall of the other of said bins, and to said vertical air passageway; and blower means for forcing air through the passageway in the upward direction.

3. A refrigerated car comprising in combination, a bulkhead extending transversely of the car adjacent one end thereof for defining a bunker area, said bulkhead being open at the top and bottom thereof; a vertical partition parallel to the bulkhead and dividing the bunker area into two ice refrigerant storage bins extending transversely of the car, said bins having the bottom walls thereof spaced from the floor of the car, the bottom wall of the bin adjacent the end of the car being of heat conducting material and adapted to support Dry Ice and the bottom wall of the other bin being perforated to permit passage of air therethrough; a vertical perforated wall spaced from the bulkhead and in the bunker for forming a water ice retaining wall in said other bin, and for providing a vertical air passageway along the side of the last mentioned bin leading from the bottom of the bin to the upper opening in the bulkhead; a baffle plate extending into the bunker from the upper edge of the lower opening in the bulkhead and parallel with the car floor and intermediate the car floor and the bottom of said other bin; and blower means for forcing air through the lower opening in the bulkhead into the bunker area and beneath said baffle plate.
